D. WARD.
ENVELOPE.
APPLICATION FILED MAY 8, 1920.

Patented Oct. 10, 1922.

UNITED STATES PATENT OFFICE.

DAVID WARD, OF LEETONIA, OHIO.

ENVELOPE.

Application filed May 8, 1920. Serial No. 379,802.

To all whom it may concern:

Be it known that I, DAVID WARD, a citizen of the United States, residing at Leetonia, in the county of Columbiana and State of 5 Ohio, have invented certain new and useful Improvements in an Envelope, of which the following is a specification.

My invention relates to an envelope.

The main object of the invention is to provide an envelope having a plurality of independent compartments, one or both of which may optionally be sealed, and which is capable of expeditious manufacture in a single sheet so as to be capable of marketing 15 for universal or general use at low cost.

The invention resides in the particular features of construction, arrangement and combination of the parts hereinafter described in relation to accompanying drawings and then claimed.

In said drawings, one preferred embodiment is illustrated and therein:

Figure 1 is a plan view of the blank from which the envelope is formed;

25 Figure 2 is a perspective view of the envelope blank partially folded into envelope form;

Figure 3 is a rear view of the envelope with both sealing flaps open;

30 Figure 4 is a cross-section on the line 4—4 of Figure 3;

Figure 5 is a rear view of the envelope sealed;

Figure 6 is a cross-section on the line 6—6 35 of Figure 5, and

Figure 7 is a cross-section through the center of an envelope closed in another manner.

Referring specifically to the drawings, 40 wherein like reference characters designate like or similar parts, the envelope is formed from a blank as best illustrated in Figures 1 and 2, being cut from a single sheet of paper or other material. It has outside walls 8

45 and 9, adapted to be folded together along the dotted line 10 and an inner or dividing wall 11, extending from one end of wall 8 and being foldable against the same along the dotted line 12. Each wall 8 and 9 has

50 a sealing flap, respectively designated 13 and 14, being foldable along the dotted lines 15 and having adhesive thereon as at 16. At the free end of wall 11, a flap 17 is provided being foldable against the wall and having

adhesive thereon. Also, flaps 18, one at each 55 side of wall 9 are provided thereon and foldable against the same and have an application of adhesive thereon as shown.

In folding the blank into envelope form, the parts are positioned as in Figure 2. 60 Wall 11 is first folded along line 12 against wall 8. Flap 17, being folded against wall 11 is secured to the inner surface of wall 8 through the adhesive thereon after being moistened. Wall 9 is then folded along line 65 10 against wall 11. Flaps 18, being folded inwardly against wall 9, may then be secured to wall 8, after moistening the adhesive thereon. The envelope thus produced will have two independent compartments, one of 70 them intermediate the wall 8 and wall 11, capable of being closed by flap 13 and the other between wall 11 and wall 9 and adapted to be closed by the flap 14.

Various methods of fastening the compartments will suggest themselves. For instance, one flap may be folded inwardly intermediate one of the outer and the inner wall and the other flap extend across the insert openings and then be pasted to the exterior of one of the outer walls, as suggested in Figure 6. Also as shown in Figure 7, but one compartment need be sealed in some instances, since a sealing flap may close one insert opening and then extended into the 85 opposite compartment and sealed against the dividing wall 11. The other flap may simply be loosely folded and disposed in the opposite compartment. Many combinations and uses will be apparent and hence no 90 limitation to any particular use or method of folding is to be inferred.

Since merely one preferred embodiment has been illustrated and described, it is to be understood that changes in the details 95 falling within the spirit and scope of the appended claim, may be made.

I claim:

An envelope formed from a blank having front and back walls joined together, a flap joined to and extending from the side of the front wall, an adhesive flap formed on the free edge of said flap, said first mentioned flap being foldable against said wall and secured to the opposite side thereof by the 100 adhesive flap, the back wall being foldable 105 towards the front wall, adhesive flaps formed on the edges of said back wall for

engagement with the edges of the first mentioned flap, said back wall providing a closure for the bottom of the pocket formed by the front wall and first mentioned flap,
5 and sealing tongues formed integral with the upper edges of said walls for separately closing the compartments provided.

In testimony whereof, I have affixed my signature in the presence of two witnesses.

DAVID X WARD.
